Int. Cl. D9—05
U.S. Cl. D9—194

FIG. 1 is a front elevational view of a forcing bag for decorating pastry and the like showing my new design, the rear being a mirror image thereof;

FIG. 2 is an enlarged fragmentary front elevational view;

FIG. 3 is an enlarged fragmentary side elevational view; and

FIG. 4 is a cross-sectional view taken on line IV—IV of FIG. 2, with the thickness of the forcing bag exaggerated for better illustration.

I claim:

The ornamental design for a forcing bag for decorating pastry and the like, substantially as shown and described.
